(57) **CLAIM**

The ornamental design for an eyewear lens, as shown and described.

DESCRIPTION

FIG. 1 is a front perspective view of an eyewear lens showing our new design;

FIG. 2 is a back perspective view thereof;

FIG. 3 is a front elevational view thereof;

FIG. 4 is a rear elevational view thereof;

FIG. 5 is a left side elevational view thereof, the right side elevational view being a mirror image thereof;

FIG. 6 is a top plan view thereof; and,

FIG. 7 is a bottom plan view thereof.

The broken lines in the Figures show portions of the eyewear lens that form no part of the claimed design.
